UNITED STATES PATENT OFFICE.

EARNEST ENGLISH, OF CAIRO, ILLINOIS.

BURGLAR TRAP.

Application filed February 14, 1925. Serial No. 9,251.

This invention relates to a burglar trap for use in banks and the like, the general object of the invention being to provide means at the windows through which money is dispensed for catching and holding a burglar's arm when he attempts to seize money placed adjacent the window, with means for operating the before mentioned means by a person located on the inner side of the window.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a view of portion of a teller's cage showing my invention in use.

Figure 2 is a longitudinal sectional view through Figure 1.

Figure 3 is a sectional detail view showing the device in raised position.

Figure 4 is a similar view showing the device in lowered position.

Figure 5 is a transverse sectional view showing the means for releasing the latches so that the device can be raised.

Figure 6 is a view of one of the guides.

In these views, 1 indicates a portion of a teller's cage which is provided with the window 2 through which money is taken in and dispensed. Usually a burglar or bank robber will approach the window and hold up the officials through the window and will seize the money by reaching in through the window. In order to catch and hold a robber when he attempts to secure the money I provide a part in the window which can be lowered so as to seize and hold the arm or hand of the burglar and thus prevent him from escaping with the money. In carrying out my invention I place a cross piece 3 adjacent the center of the window to which the lower ends of the bars 4 of the window are attached. A second cross piece 5 is slidably mounted in the window below the cross piece 3 by having its grooved ends engaging the vertical guides 6 placed at the sides of the window. These guides are of channel shape in cross section and

are provided with notches 7. An upright 8 is connected with the center of the cross piece 5 and passes through a central guiding opening 9 in the cross piece 3 and bars 10 are connected with the cross piece 5 and pass through guiding holes 9' in the cross piece 3. Pointed bars 11 have their upper ends inserted in holes in the lower edge of the cross piece 5 and the weight of the cross piece 5 and the parts carried thereby is such that it will drop under the action of gravity until the pointed ends of the bars 11 rest upon the counter or sill 12 of the window. The bars 11 are placed close enough together as to prevent a person's hand from being pulled between the same. A pair of spring actuated latch members 13 are arranged in the cross piece 3 for engaging keeper notches 14 in the guiding member 8 for holding the cross piece 5 in raised position. Cables 15 are connected with these latch members and pass over guiding pulleys 16 through the channels formed by the guides 6 to a point below the counter or sill 12 where they pass over guide pulleys 17 and have their lower ends attached to a pedal bar 18 which is designed to be depressed by the foot of a teller or other official in the cage to cause the cables to move the latch members 13 to releasing position so that the cross piece 5 can drop. This cross piece is provided with the spring actuated latch members 19 for engaging the notches 7 in the guides 6 for holding the cross piece in lowered position.

A knob 20 is carried by the cross piece 5 and is connected to the inner ends of the latch members 19 by the members 21 so that when this knob is turned the latch members 19 will be retracted so that the cross piece 5 can be raised. The handle of the knob projects from the inner face of the cross piece 5 so that it can be seized by an official within the cage and cannot be operated from outside the cage.

From the foregoing it will be seen that the trap is set by raising the cross bar 5 until the notches 14 are engaged by the latches 13 which will hold the device in raised position, as shown in Figures 1 and 3. This will permit free use of the window. If an attempt is made to rob the bank the robber would naturally place his arm through the window to grasp the money and then the teller would simply step on the bar 18, which, through the cables 15, would retract the latches 13, thus permitting the bar

5 to drop upon the arm of the robber and thus hold him at the window and prevent him from escaping. He could not raise the bar 5 to effect his escape as it is locked 10 in lowered position by the latches 19 engaging the notches 7. After the robber has been secured he can be released by turning the knob 20 from inside the cage to retract the latches 19 and the bar 5 raised.

10 It is thought from the foregoing description that the advantages and novel features of my invention will be readily apparent.

I desire it to be understood that I may make changes in the construction and in the 15 combination and arrangement of the several parts, provided that such changes fall within the scope of the appended claims.

What I claim is:—

1. In combination with a window opening 20 and channel shaped guides upon opposite sides of the opening formed with notches in their lower ends, of a stationary cross piece between the guides above the notched portions, a movable cross piece between the 25 guides and having an upright movable through the stationary cross piece, spring actuated means cooperating with the upright for retaining the movable cross piece in a raised position, pointed bars attached 30 to the lower edge of the movable cross piece and arranged in spaced relation, means whereby to disengage said spring means

from the upright to permit the movable cross piece to move downwardly from the stationary cross piece and means carried 35 by the movable cross piece for engaging the notches in order to retain the movable cross piece when in its lowered position, said last means being manually actuated to release said movable cross piece. 40

2. In combination with a window opening and channel shaped guides upon opposite sides of the opening, having notches therein located adjacent one end, of a stationary cross piece positioned between the guides 45 and having an opening therethrough, a movable cross piece between the guides, an upright carried thereby and movable through the opening in the stationary cross piece, means carried by the stationary cross piece 50 and engaging the upright for retaining the movable cross piece in a raised position, spaced pointed bars carried by the movable cross piece, manually actuated means whereby to release the movable cross piece to permit the same to move away from the stationary cross piece, means carried by the movable cross piece and engaging the notches for retaining the said last cross piece against movement and manually operating means for releasing said last cross piece. 55 60

In testimony whereof I affix my signature.
